UNITED STATES PATENT OFFICE.

JOHN F. GOLDFING, OF WASHINGTON, DISTRICT OF COLUMBIA.

DOOR-HOLDER.

1,255,408.

Specification of Letters Patent.

Patented Feb. 5, 1918.

Application filed May 29, 1915. Serial No. 31,255.

To all whom it may concern:

Be it known that I, JOHN F. GOLDFING, a citizen of the United States, residing at Washington, District of Columbia, have invented certain new and useful Improvements in Door-Holders, of which the following is a specification.

My invention relates to door checks or holders whose function it is, when attached to the door, to hold the same open or partly open and prevent its slamming or closing.

The invention further relates to such a device which, automatically and without adjustment by the hand or feet has the four functions: to offer no resistance to the opening of the door; to offer a temporary resistance to the closing of the door from any open or partly open position, such resistance being sufficient to prevent accidental closing of the door; to yield to a sufficiently strong push or pull on the door when it is desired to close it; and to assume an inoperative position after it so yields, so that it is then ready to perform its first mentioned function of non-resistance.

The invention has for its object to construct and provide a door holder or check which will have the above described mode of operation and useful functions; and it consists in the parts and combinations thereof hereinafter described and pointed out in the claims.

In order to make my invention more clearly understood I have shown in the accompanying drawings means for carrying the same into practical effect, without limiting my improvements, in their useful applications, to the particular constructions which, for the purpose of explanation, I have illustrated.

In said drawings:—

Figure 1 is a side elevation of a door holder or check embodying my invention, and an edge view of a portion of a door to which the same is attached, the holder being in the position it takes when the door is closed.

Fig. 2 is a similar view, with the device in the position which it takes in the act of opening the door and when the door has been opened two or three inches, more or less (referring to the particular scale of the drawing).

Fig. 3 is a similar view, with the holder in the position which it takes when the door

has been opened for four or five inches or to a greater distance or entirely.

Fig. 4 is a sectional view on line IV—IV of Fig. 2.

Fig. 5 is a horizontal section on line V—V 60 of Fig. 4.

Fig. 6 is a vertical sectional view of the holder, a portion of the spring being broken away, with the parts in the position which they assume immediately after the holder 65 has ceased to offer its temporary resistance to the closing of the door.

Fig. 7 is a perspective view of the lower member of the holder, the other parts being detached therefrom. 70

Referring to the drawings, 1 is a portion of an ordinary swinging door to which the holder is shown as applied, the bottom edge of the door being indicated at 2. 3 is a flexible spring arm which can be of various 75 shapes not inconsistent with the useful operation of the device, the preferred shape being about semi-circular, with an integral extension 4 which is or may be rigidly attached to the door, by screws 5 or other suitable means. At its free end, which is adapted to have an up and down spring yielding motion, the arm 3 carries a pivot 6. This is preferably accomplished by forming the end of the spring with an eye or bearing 7 85 into which the pivot is inserted.

10 is a swingable leg comprising an upper member 11 and a lower member 12 connected by a suitable pivot 13. In the construction illustrated the pivot 13 is shown 90 as consisting of two trunnions formed integral with the member 12 (Fig. 7). The upper member 11 consists preferably of two links hung on the ends of the pivot 6. The said ends are riveted at 14 sufficiently to retain the links in the position illustrated.

The ends of the pivot elements 13 are also riveted over the lower ends of the links as indicated at 15. The said riveted parts do not bear tightly on the links but allow the 100 free movement of the leg elements on both of said pivots. The lower leg element is extended above the pivot 13 between said links, as indicated at 16, and is formed with lateral shoulders 17 which may bear against 105 the edge of the upper leg element, on the side of the same toward the door (Fig. 3). This engagement takes place when the axis of the pivot 13 is a little to the outer side of a straight line which would connect the axis 110

of the pivot 6 with the point at which the lower extremity of the device bears upon the floor. The parts 11 and 12 thus have a toggle action, the toggle being locked when 5 the shoulders 17 bear against the upper leg element.

The lower end of the part 12 is screw threaded as indicated at 18 to receive the nut 19 and a soft rubber foot 20. This construction 10 enables the said foot to be screwed up or down to regulate the operative length of the leg, and the foot is held in adjusted position and from working up by the nut 19.

Other forms of foot and adjusting means, 15 are within the scope of my invention.

Such being the preferred construction of the device its operation is as follows:

When the door to which the holder is applied was last closed the parts were left 20 substantially in the position shown in Fig. 1. If the door is now opened the leg element 11 will be carried over by the pivot 6 to the position indicated in Fig. 2, and away from the shoulders 17. This movement 25 will tip the lower element 12 into substantially upright position, and a further opening of the door will cause the leg to trail after the pivot 6 in substantially the position shown in full lines in Fig. 3. It will be seen that in the above described 30 opening movement of the door the leg offers no resistance, and the door may be opened as far as desired, or entirely. But the door cannot now be accidentally closed, 35 because the toggle has become locked (Fig. 3) and presents a stiff leg between the pivot 6 and the floor. In this position the holder offers a temporary, and efficient, resistance to any closing movement of the door. If the door be intentionally pulled or pushed, 40 ordinarily by the knob, the foot 20 will not slide on the floor but will engage the same and the pivot 6 will be moved over to a position substantially perpendicular above the foot, 45 the leg being turned over to the position shown in dotted lines in Fig. 3, thereby pushing up the pivot 6 and flexing the spring 3, the resistance of which spring has to be overcome in this operation. From this 50 last mentioned position the spring offers no further resistance to the closing of the door, and even assists the same, until the spring returns to normal position, and in such further closing of the door the leg tips 55 over to substantially the position shown in Fig. 6 and thereafter trails after the pivot 6 until the door is closed, thus automatically assuming the inoperative and non-resistant position shown in Fig. 1.

In applying the holder to a door the foot 60 20 is located on the lower leg element so that it may be screwed further upward, and the spring extension 4 is attached to the door at such height as will give the 65 proper inclination to the leg when the latter

is in the position shown in Fig. 3, so that the foot will not slide on the floor but will take hold of the same and cause the leg to turn. If, on trying the operation of the holder, its temporary resistance is found to 70 be too strong the nut 19 and foot 20 are screwed farther upward on the leg until such resistance is sufficient for the purpose but not too much.

21 is a rubber buffer attached to the outer 75 end of the spring 3, the spring acting mainly as the buffer and the rubber 21 preventing any marring of the wall against which the door may be swung.

It is seen from the above that the improved door holder is provided with means whereby the spring is flexed temporarily during the first part of the closing movement of the door, as the pivot 6 passes the vertical plane of the leg, and whereby the 85 leg automatically assumes an inoperative trailing position in either direction, with the spring normal, except during said time when the spring is flexed.

The holder having the described mode of 90 operation is particularly useful on uneven floors. To illustrate, it often happens that the floor is higher near the door sill than it is farther back where it is desired that the device shall hold the door open. If the 95 holder resisted in both directions it would have an objectionably strong resistance to opening the door in order that it might have a sufficient resistance at the holding point. It is readily seen that my improved holder 100 obviates such difficulties.

What I claim is:

1. A door holder comprising a swingable leg having a floor-engaging foot, and a pivot for said leg, said holder having a flexible 105 spring, and means comprising two pivotally connected members which form said leg whereby the spring is flexed temporarily during the first part of the closing movement of the door and whereby the leg automatically assumes an inoperative trailing position in either direction except during said 110 time when the spring is flexed.

2. A door holder comprising a swingable leg having a floor-engaging foot, and a pivot 115 for said leg, said holder having a flexible spring, and means comprising two pivotally connected members which form said leg whereby the spring is flexed temporarily as the leg assumes a vertical position during 120 the first part of the closing movement of the door and whereby the leg automatically assumes a vertical position without flexure of the spring during the opening movement of the door and an inoperative trailing position 125 in either direction except during said time when the spring is flexed.

3. A door holder comprising a swingable leg having a floor-engaging foot, and a pivot for said leg, said holder having a flexible 130

spring, and means comprising two pivotally connected members which form said leg whereby said leg causes the flexure of the spring as the pivot passes the vertical plane of the leg on the closing movement of the door and leaves the spring normal as the pivot passes said plane on the opening movement of the door.

4. A door holder comprising a swingable leg having a floor-engaging foot, and a pivot for said leg, said holder having a flexible spring, and means, comprising two pivotally connected members which form said leg and a shoulder, which cause the flexure of the spring as the pivot passes the vertical plane of the leg on the closing movement of the door and leaves said spring normal as the pivot passes said vertical plane on the opening movement of the door.

5. In a door holder, in combination: a swingable leg comprising two pivotally connected parts; a pivot on which the leg is mounted to swing away from or toward the door; and means for attaching the leg and pivot to the door; said parts comprising a spring which is operated when the leg swings in vertical line with said pivot on the closing movement of the door, the spring being inoperative to resist the opening of the door when the leg swings in line with its pivot on such opening movement.

6. A door check or holder comprising, in combination: an arm having means for attachment to a door; a pivot parallel with the front of the door and carried by the arm at a distance from the door; and a swingable leg comprising two pivotally connected parts connected with the said pivot and freely swingable in either direction to trail on the floor without resistance, said leg having a

foot which rests on the floor and engages the same, with resistance to hold the door when the door is pressed in the direction opposite to the inclination of the said swingable leg; the said parts comprising a metal spring interposed between the said foot and the said attaching means.

7. In a door holder, in combination: a pivot; means for attaching the same to a door; and an automatic, temporarily resist- 50 ant, and trailing leg comprising two pivotally connected parts swingably mounted on the said pivot and having a floor-engaging foot, the said parts comprising a flexible spring interposed between the said foot and the said attaching means and acting against the said pivot.

8. In a door holder, a flexible spring and a swingable leg freely pivoted thereto and consisting of a toggle of two elements. 60

9. In a door holder, a flexible spring, a swingable leg freely pivoted thereto and inclinable toward or from the door and formed of two parts pivotally connected and having relative movement, and means for extending and shortening the operative length of said leg. 65

10. In a door holder, a flexible spring, a pivot carried at the free end of the spring, a swingable leg mounted on said pivot and adapted to engage the floor and swing under the pivot to either side of the same as described, and formed of two parts pivotally connected and having relative movement and means for changing the distance to which the pivot is raised above the floor by the said swinging of the leg under the same. 75

In testimony whereof I affix my signature hereto.

JOHN F. GOLDRING.
